[57] **CLAIM**

The ornamental design for a hand held telephone set, as shown.

DESCRIPTION

FIG. 1 is a perspective view of a hand held telephone set, showing my new design;

FIG. 2 is a top plan view thereof;

FIG. 3 is a side elevational view thereof, the opposite side being a mirror image of the side shown; and

FIG. 4 is a front elevation thereof.

FIG. 1

FIG. 2

FIG. 3

FIG. 4
